UNITED STATES PATENT OFFICE.

HYMAN MAIMIN, OF NEW YORK, N. Y., ASSIGNOR TO H. MAIMIN CO., INC., A CORPORATION OF NEW YORK.

STRIPPER-FOOT FOR CLOTH-CUTTING MACHINES.

1,290,272.

Specification of Letters Patent.

Patented Jan. 7, 1919.

Application filed February 14, 1917. Serial No. 148,538.

To all whom it may concern:

Be it known that I, HYMAN MAIMIN, a citizen of the United States, residing in the city, county, and State of New York, have 5 invented certain new and useful Improvements in Stripper-Feet for Cloth-Cutting Machines; and I do hereby declare the following to be a full, clear, and exact description of the invention, such as will enable 10 others skilled in the art to which it appertains to make and use the same.

This invention relates to presser feet or strippers for cloth cutting machines and has been particularly applied to that type of a 15 machine in which there is employed a reciprocating knife having a vertical cutting edge. It is common in such machines to form the presser foot with a convex under surface which permits an easy entry of the 20 cloth to be cut. The presser foot is extended rearwardly in a forked shape, and sometimes made to extend completely to the rear of the knife standard. In some instances the 25 curvature of the foot is such that the point of maximum pressure is immediately beneath the shank of the presser foot and well forward of the knife. In other instances, and more commonly, the curvature is such that the region of maximum pressure is 30 along the sides of the knife or knife-standard, the flat under surfaces of the two prongs of the fork establishing extended stripping surfaces of substantially equal pressure throughout the region at both sides of the 35 cutting edge and the region immediately in front thereof. It is common practice with such machines to encounter a checking of the forward movement of the machine, and often a swerving from the intended line of cutting, 40 as well as a delay in the cutting operation, due to the puckering or bunching of the cloth under the stripper foot.

I have discovered that a remarkably effective stripper foot, which eliminates all 45 lifting and puckering of the cloth, may be produced by so shaping the stripper foot that the stripping pressure is concentrated in two projecting tongues or fingers lying close to the line of cut and a short distance 50 in front of the vertical cutting edge of the knife. The arrangement is particularly effective if the projecting tongues or fingers are produced by cutting away the stripper foot between its shank and the forward edge 55 of the knife to form a sight opening, the

rearward extremities of which constitute the projecting tongues or fingers. This arrangement, in combination with a proper shaping of the under surface of the stripper foot, not only affords a definite sight opening through 60 which the line of cut may be observed, but also has the beneficial effect of relieving the pressure on the cloth at the region immediately ahead of the stripper tongues or fingers.

The invention will be understood more 65 clearly from the following description when taken in connection with the accompanying drawing illustrating a preferred form of the invention.

In this drawing, Figure 1 is a front elevation showing the base-plate, knife and standard of a cloth cutting machine, and showing such machine equipped with a combined knife guard and stripper-foot structure of the flying wing type illustrated in 70 my Patent No. 1,207,780 of December 12, 1916; Fig. 2 is a view in side elevation looking to the left of Fig. 1; Fig. 3 is a view similar to Fig. 2 but looking to the right of Fig. 1, and showing a pile of cloth as acted 75 on by the stripper foot; and Fig. 4 is a horizontal section taken on line 4—4 of Fig. 3, with the pile of cloth removed.

The cloth cutting machine here illustrated has a base-plate 5, a standard 6, a knife 7 85 and an adjustable block 8, all of standard construction. This block 8 has pivotally mounted thereon a pair of intermeshing gears 9, provided with offset arms to which are secured guard-members 11, the guard- 90 members carrying at their lower ends a pair of complementary stripper-foot sections or wing-members 12 and 13, and the block 8 being vertically adjustable on the standard 6 to arrange the stripper-foot structure at the 95 proper height above the base-plate 5 to compress any desired pile of cloth, all as is well known. A compression spring 14 is anchored at its opposite ends to studs carried by the intermeshing gears 9, this arrangement permitting a single spring to yieldingly hold the complementary stripper foot wing-members 12 and 13 in either of their extreme positions of adjustment, that is, this spring tends to hold the wing-members 100 whether they are interengaged to embrace the knife-blade as illustrated, or whether they have been swept upward and away from the knife and hold the wing members at 105 opposite sides of and above the knife to 110

facilitate sharpening as is shown in my patent referred to above.

In order that the stripper foot sections may be positively locked together when arranged to embrace the knife 7, complementary latch elements are carried by the wing-members 12 and 13. As shown most clearly in Fig. 4, wing-member 12 has a laterally offset extension 15 provided with a suitable latch recess which receives a keeper formed by the downturned end of a latch-lever 16 as shown. This lever is pivoted on the usual forward extension of wing-member 13; this extension being provided to serve as a guide for the operator so that he may easily follow the proposed line of cut as marked on the goods. A suitable spring 17 is associated with the latch lever, and the laterally offset extension 15 of wing member 12 is slightly ramped as indicated at 15^a in Fig. 4 whereby as the guard members 11 are lowered to bring the wing-members 12 and 13 together the latch elements carried by said wing members are automatically snapped into locking engagement.

It will be noted that when the stripper foot structure is assembled to embrace the knife, such structure forms a fork within which is extended the knife 7 with the vertical cutting edge thereof nearest to the bend in the fork. In other words, there is provided a U-shaped structure which embraces the forward cutting edge and sides of the knife but which is not extended far enough in rear of the vertical cutting edge of the knife to embrace the back portion of the knife standard.

The knife-adjacent edge of wing-member 13 is notched as shown at 18 and the knife adjacent edge of the wing member 12 is notched at 20, these notches together forming a sight opening in front of the knife edge. The portions of the two wing-members ahead of the sight opening serve, because of the convex shape of the under surface of the stripper foot, to gradually compress the layers of cloth between the presser foot and the baseplate. The portions of the stripper foot in rear of the notches 18 and 20 constituting the sight opening are curved upwardly as shown to gradually release the pressure on the cut cloth. Closely adjacent to the line of cut on opposite sides thereof, and a short distance in front of the cutting edge of the knives, the projections or fingers 19 and 21, which are formed by the termination of the respective notches 18 and 20, serve as stripping points, comparable in their effect to that which would be produced by the fingers of the operator placed at these points and firmly pressed downwardly. It is found that the best effect is produced if these projections or fingers are staggered, so that one is slightly farther ahead of the knife edge than the other, although this ar-

rangement is not essential. In the particular embodiment of the invention which I prefer, the projection 21 is spaced approximately one-sixteenth of an inch ahead of the vertical cutting edge of the knife and the projection 19 is slightly ahead of the projection 21.

In order to concentrate the stripping pressure at the region of these stripping projections or fingers, the convex under-surfaces of the wing members 12 and 13 are shaped to compress the pile of goods with maximum effect at a point 22, a certain distance ahead of the path of descent of the vertical cutting edge of the knife, as indicated at 23 in Fig. 3. The distance 23 marks the degree of separation of the vertical cutting edge of the knife preferably from the corner 19 in the direction of the proposed line of cut. Thus in Fig. 2, where the line V—V' represents the line of descent of the vertical cutting edge of the knife and the line H—H' is arranged at right angles to the line V—V' and parallel to the top face of the baseplate 5 the line H—H' contacts the convex undersurface of the stripper foot, at a point T located said distance 23 ahead of the vertical cutting edge of the knife; and it will be observed that either wing-member is shaped to compress the pile of goods with maximum effect at the point T but with less and less effect at points between said point T and the rear end of the wing-member.

I claim:

1. In a cloth cutting machine having a base plate which supports a knife and knife standard so that the base plate may be passed under a pile of fabric to advance the standard through the pile while said pile is being cut, a stripper foot member having a curved lower surface provided with means for producing a maximum compression of the pile of fabric between said member and the base plate at points on opposite sides of the line of cut and slightly ahead of the knife.

2. In a cloth cutting machine having a base plate which supports a knife and knife standard so that the base plate may be passed under a pile of fabric to advance the standard through the pile while said pile is being cut, a stripper foot member having a curved lower surface provided with means for producing a maximum compression of the pile of fabric between said member and the base plate at points on opposite sides and closely adjacent to the line of cut and slightly ahead of the knife.

3. In a cloth cutting machine having a base plate which supports a knife and knife standard so that the base plate may be passed under a pile of fabric to advance the standard through the pile while said pile is being cut, a stripper foot member having a curved lower surface provided

with a sight opening lying in advance of the knife, and means for producing a maximum compression of the pile of fabric between said member and the base plate at points on opposite sides of the line of cut and between the knife and the sight opening.

4. In a cloth cutting machine having a knife and a knife-holding standard, a combined knife guard and stripper foot having 10 a pair of separate guard members pivotally supported to swing away from the path of the knife in a plane substantially normal thereto, and two complementary stripper foot sections carried by the guard members, 15 these complementary stripper foot sections when joined forming a U-shaped structure which is disposed to embrace the vertical cutting edge and sides of the knife to completely protect said cutting edge and to effectively hold down the cloth at points on 20 opposite sides of the line of cut and slightly ahead of the vertical cutting edge of the knife.

5. In a cloth cutting machine of the kind 25 described, a stripper-foot consisting of two complementary sections shaped to form a fork within which the cutting edge of the knife is extended so that during operation of the knife the stripper-foot overlies the 30 uncut cloth ahead of the knife and holds the same down at points on opposite sides of the line of cut, one of the sections being notched in its knife-adjacent edge to provide a cloth-compressing corner at a point 35 closely adjacent to the line of cut and slightly ahead of the vertical cutting edge of the knife.

6. In a cloth cutting machine of the kind 40 described, a stripper-foot consisting of two complementary sections shaped to form a fork within which the cutting edge of the knife is extended so that during operation of the knife the stripper-foot overlies the 45 uncut cloth ahead of the knife and holds the same down at points on opposite sides of the line of cut, one of the sections being notched in its knife-adjacent edge to provide a cloth-compressing corner at a point closely 50 adjacent to the line of cut and slightly ahead of the vertical cutting edge of the knife, and the other section being notched in its knife adjacent edge slightly ahead of the notch in the first section to form a second cloth-compressing corner at a point 55 closely adjacent to and on the opposite side of the line of cut.

7. In a cloth cutting machine having a base plate which supports a knife and knife

standard so that the base plate may be passed under a pile of fabric to advance the 60 standard through the pile while said pile is being cut, a stripper foot member having a curved lower surface provided with means for producing a maximum compression of the pile of fabric between said member and the base plate at points on opposite sides of the line of cut and at different distances 65 slightly ahead of the knife.

8. In a cloth-cutting machine having a base-plate which supports a knife and knife- 70 standard so that the base-plate may be passed under a pile of fabric to advance the standard through the pile while such pile is being cut, a stripper foot formed and arranged to press down on and compress the 75 pile between itself and the base-plate at points on opposite sides of and closely adjacent to the line of cut, each of said points being a short distance forward of the cutting edge of the knife, and one of said 80 points being slightly ahead of the other.

9. In a cloth-cutting machine having a base-plate which supports a knife and knife- 85 standard so that the base-plate may be passed under a pile of fabric to advance the standard through the pile while such pile is being cut, a stripper foot member formed and arranged to press down on the pile to compress the pile between such member and the base-plate with maximum effect at 90 points on opposite sides of the line of cut and slightly ahead of the knife, and a sight opening in the stripper foot member lying in advance of said points of maximum effect.

10. In a cloth-cutting machine having a 95 base-plate which supports a knife and knife- standard so that the base-plate may be passed under a pile of fabric to advance the standard through the pile while such pile is being cut, a stripper foot member 100 formed and arranged to press down on the pile to compress the pile between such member and the base-plate, and having in its rearward portion a fork to straddle the knife and standard, and being cut away to 105 form a sight opening, the rearward extremities of which lie in the prongs of the fork to form projecting tongues or fingers lying close to the opposite sides of the line of cut and slightly in front of the edge of 110 the knife, the under surface of the presser foot being so shaped as to concentrate the stripping pressure at the region of the said projections or fingers.

In testimony whereof I affix my signature. 115
HYMAN MAIMIN.
